UNITED STATES PATENT OFFICE.

CLARENCE S. MOORE AND WILLIAM G. THOMAS, OF LEXINGTON,
KENTUCKY.

DRIER.

No. 829,028.

Specification of Letters Patent.

Patented Aug. 21, 1906.

Application filed November 28, 1904. Serial No. 234,824.

To all whom it may concern:

Be it known that we, CLARENCE S. MOORE and WILLIAM G. THOMAS, citizens of the United States, residing at Lexington, in the county of Fayette and State of Kentucky, have invented certain new and useful Improvements in Driers, of which the following is a specification.

Our invention relates to driers, and especially to that class of driers provided with an endless carrier.

The object of our invention is to provide a drier especially adapted for use in laundries, wherein the maximum amount of drying will be accomplished by the expenditure of a minimum amount of steam.

A further object of our invention is to provide improved means for exerting a tension upon the endless cable.

20 A further object of our invention is to provide an improved carrier particularly adapted for carrying linen into and through the dry-room and which shall be particularly reliable in both retaining the linen and dis-
25 charging it at the stripper.

A further object of our invention is to provide improved guideways at the points where the carriers enter and leave the dry-room.

30 A further object of our invention is to provide guide-wires throughout practically the entire course of the carrier.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made 35
40 within the scope of the claims without departing from the spirit or sacrificing any of the advantages of the invention.

In the drawings, Figure 1 is a view in front elevation of our improved dry-room. Fig. 2 is a top plan view of our drier, showing the gearing disposed upon the top of the dry-room. Fig. 3 is a vertical sectional view of our improved drier, taken on line 3 3 of Fig. 2. Fig. 4 is a top plan detail view of the device for exerting tension upon the endless cable. Fig. 5 is a view in side elevation of the cable-support and pulley located without the dry-room. Fig. 6 is a vertical sectional view in detail of the tension-exerting mechan-

ism. Fig. 7 is a detail view in side elevation 55 of the cable and carriers and showing the guideways in longitudinal section. Fig. 8 is a transverse sectional view of the guideways and cable, showing the carrier, stripper, and stripper-trip in elevation. Fig. 9 is a view in 60 side elevation of the cable-carrying pulley disposed within the dry-room and also showing the brackets for carrying the guide-wires. Fig. 10 is a view of a carrier in side elevation, showing its use in carrying a form for sus- 65 pending a shirt or other garment. Fig. 11 is a detail sectional view of the carrier. Fig. 12 is a view in elevation of the carrier-shank and cross-arms, showing in section means for connecting the carrier-hook. Fig. 13 is a plan 70 view of one of the cable-carrying pulleys, showing the seats for receiving the carrier cross-heads and the disposition of the guide-wires relative thereto.

Like characters of reference designate cor- 75 responding parts throughout the several views.

In the preferred embodiment of our invention we construct a dry-room from two thicknesses of lumber 1 and 2, preferably disposed at angles to each other and line the said dry-room internally with a heat-resist- 80 ing substance, as sheet-asbestos, and an inter- 85 lining of sheet metal, as tin. Within the dry-room we dispose a heat-radiating surface, 90 as the steam-coils 5, in the form of a hollow square and spaced at approximately equal distances from three sides of the dry-room with the open side disposed toward the front, to which communication may be had 95 through the door 6. Adjacent to the top of the dry-room and above the heat-radiator are rotatably mounted one or more fans, 7 with means for rotating, as the pulleys 8 and 95 belts 9, receiving motion from a pulley 10, mounted upon a shaft 11, which may receive motion from a line-shaft by means of the pulley 12.

Within the dry-room and adjacent to the corners opposite the front are suspended 100 near the top cable-carrying pulleys 13 in any convenient manner, as by the brackets 14. A second pair of cable-carrying pulleys, like- 105 wise carried by brackets similar to 14, are mounted from the top of the dry-room in a horizontal plane with pulleys 13 and upon a line which bisects the angle at the corner of the room. Adjacent to the door is suspend-

ed a pulley 16 in a plane with pulleys 13 and 15. Adjacent and parallel openings 17 and 18 are provided in the front of the dry-room and outstanding from said dry-room adjacent to said openings is provided a plurality of brace-rods 19. At the extremity of the brace-rods 19 is provided an adjustable bearing 20, designed to tighten the cable 22, hereinafter referred to. This bearing is rotatably mounted, a cable-carrying pulley 21 in horizontal plane with the pulleys 13, 15, and 16 within the dry-room. Upon the said cable-carrying pulleys is mounted an endless cable 22 in such manner that passing into the dry-room through the opening 17 it is passed around pulleys 13, 16, and 15, respectively, out through opening 18, and about pulley 21. The adjustable bearing 20 is mounted upon a plate 23, carried at the extremities of brace-rods 19. The plate 23 is provided with slots 24, and bolts 25, slidably disposed within said slots, are rigidly secured to the adjustable bearing 20. To support the bearing 20 and pulley 21, a supporting-rod 26 may be secured to the plate 23 and to any convenient stationary object 27, which may be the top of the room in which the drier is located. A plurality of carriers 28 are equally spaced upon cable 22. The carrier 28 comprises a cross-head 29, provided centrally with a cable-receiving opening. A shank 30 is provided with screw-threads 31, and a screw-threaded opening is provided in the cross-head 29 at right angles to the cable-receiving opening and adapted to engage the screw-threads 31 of shank 30. The shank 30 is adapted to be screwed within the screw-threaded opening of cross-head 29 until the screw-threaded portion 31 grips the cable 22 and rigidly secures the cross-head 29 to the cable. When a desired degree of gripping tension has been applied to secure the cross-head to the cable, a lock-nut 32 upon the screw-threads 31 is screwed against the cross-head 29. The shank 30 is provided with a cross-arm 33 adjacent to the end opposite the screw-threads 31. Adjacent to the extremes of the cross-arms 33 are provided openings 34, in which are disposed carrier-hooks 35, and secured therein by screws 36, entering the cross-arms 33 axially and forcibly abutting the carrier-hook 35. The carrier-hook 35 is disposed outwardly from the cross-arm 33 and given an upward turn. A second cross-arm 37 is secured to the shank 30 at a point adjacent to the lock-nut 32. To the outer extremities of the cross-arm 37 are pivotally secured strippers 38, which are provided with slots 39, embracing the carrier-hook 35. A guard or closure 40, integral with the stripper 38, is adapted to abut the outer end of carrier-hook 35.

Within the openings 17 and 18 are disposed hollow guides 41 and 42, having an internal cross-section conforming substantially

in form and proportion to cross-head 29 and provided along their lower sides with openings, as at 43. A pair of guide-wires 44 are secured to the bearing-plate 23, as by brackets 45, and are disposed to engage the under side of cross-heads 29. The wires 44 extend within the dry-room and throughout the entire course of the cable 22 therein and are supported at the several turns, as by brackets 46. Upon the guideway 42 is secured a stripper-trip 47, consisting of a substantially square frame through which the carrier-shank 30 may pass unobstructedly, but in the path of the stripper 38, so that, as shown in Fig. 7, the stripper 38 will engage the lower bar of the stripper-trip and sliding outwardly upon the carrier-hook 35 will discharge from said carrier-hook any article thereon suspended, as the cuff 48. The cable 22, with its carriers 28, are given motion through pulley 16, which is provided with a shaft 49, extending upwardly through the top of the dry-room and provided on its upper end with a gear 50, engaging a worm-gear 51 upon shaft 52. The shaft 52 is provided with a pulley 53, which may receive motion from the shaft 11 by means of belt 54 and pulley 55. The pulley 55 may be stepped, as shown, to vary the speed of the pulley 16 and cable 22. The cable-carrying pulleys and the radiator 5 are so disposed that the radiator occupies a space substantially midway between the convolutions of the cable 22 within the dry-room and extending from near the bottom of said dry-room to a point adjacent to the vertical height of the cable. The openings 17 and 18 within the front of the dry-room are supplied with sliding cover members 56 and 57, adapted to vary the size of the openings 17 and 18 for use in connection with garments of various sizes.

The operation of our improved drier is as follows: With the power applied to rotate the cable in the direction indicated by the arrow, the fans will be rotated to force air downwardly. Articles to be dried will be hung upon the carrier-hooks 35 and will pass into the dry-room through openings 17, the cross-head 29 being held in alinement by the guideway 41. The article attached to the cable will traverse the dry-room adjacent to its outer walls around pulleys 13 and 16 and back within the hollow square formed by the radiator 5, around pulleys 15, and out through opening 18. In passing through opening 18 the cross-head 29 will be held in alinement by guideway 42, and stripper 38 will contact with the lower bar of stripper-trip 47, disengaging any article hung thereon, which is permitted to drop into a receptacle below. The rotation of the fans force the air within the dry-room downwardly and out through an opening 18^a, conveniently disposed adjacent the bottom, fresh air being drawn in as required through openings 17 and 18.

It is obvious that many changes in the construction and detail of our drier may be made without departing from the spirit of the invention or the scope of the claims.

Having thus described our invention, what we claim as novel, and desire to secure by Letters Patent, is—

1. In a drier, a dry-room, heat-radiators located therein, an endless carrying-cable 10 above and at each side of said radiators, a carrier, having an angular cross-head and provided with a hook and stripper, a hollow guide secured to said dry-room where the cable emerges therefrom and conforming internally in cross-section to the shape of the cross-head and a stripper-trip secured to the guide and disposed in the path of the stripper.
2. In a drier, a dry-room, heat-radiators therein, an endless carrying-cable mounted 20 partly within and partly without the dry-room and disposed to travel above and at each side of the radiators throughout their entire length, carriers attached to said cable, each carrier comprising a shank and a hook 25 outstanding therefrom, a stripper provided with a slot and pivoted to the shank with the hook passing through the slot and a closure integral with the stripper and disposed to abut the outer end of the hook.
3. In a drier, a dry-room, heat-radiators therein, an endless carrying-cable mounted principally within but extending without the dry-room disposed to travel on a substantially horizontal plane throughout the entire 35 course and above and at each side of the heat-radiators, means without the dry-room for regulating the tension of the cable, carriers attached to said cable, each carrier comprising a shank and a hook outstanding therefrom, a stripper provided with a slot and pivoted to the shank with the hook passing through the slot and a closure integral with

the stripper and disposed to abut the outer end of the hook.

4. In a drier, a dry-room, an endless cable, 45 a carrier, having an angular cross-head and provided with a hook and stripper, a hollow guide secured to said dry-room where the cable emerges therefrom and conforming internally in cross-section to the shape of the cross-head and a stripper-trip secured to the guide and disposed in the path of the stripper.

5. In a drier, a carrier adapted to be attached to a cable and comprising a cross-head provided with a cable-receiving opening, a shank adapted to grip the cable and hold the carrier thereon, cross-arms secured to said shank, an outstanding upturned hook secured to one cross-arm and provided with a slot with the hook passing therethrough, and 60 a closure integral with the stripper and adapted to abut the end of the hook.

6. In a drier, a cable, a carrier adapted to be attached to the cable and comprising a cross-head provided with a cable-receiving 65 opening, a shaft adapted to grip the cable and hold the carrier thereon, cross-arms secured to said shank, an outstanding upturned hook secured to one cross-arm, a stripper pivoted to the other cross-arm and provided with 70 a slot with the hook passing therethrough, a closure integral with the stripper and adapted to abut the end of the hook and a stripper-trip disposed in the path of the stripper and adapted to manipulate the stripper to remove 75 any article suspended from the hook.

In testimony whereof we affix our signatures in presence of two witnesses.
